UNITED STATES PATENT OFFICE

2,459,312

LIQUID CIRCULATOR

Bryant Essick, Los Angeles, Calif.

Application September 15, 1945, Serial No. 616,513

2 Claims. (Cl. 103—87)

1

This invention has to do with a liquid circulator and is more particularly concerned with a unit involving, in combination, a simple rotary pump and an electrical motor for driving the pump. It is a general object of the invention to provide a device of the general character referred to which is highly efficient and dependable in operation, at the same time being extremely simple and inexpensive of construction.

There are numerous situations where it is desired to pump or circulate liquids such, for instance, as water, and where economy of operation is essential and at the same time it is important that the operation be dependable and uniform. An example of such a situation is an air cooler of the evaporative type wherein water is circulated over an evaporative pad, or the like. In such devices a small stream of water must be constantly maintained and from a commercial standpoint, simplicity and economy of construction are highly important.

An object of my present invention is to provide a circulator for water, or the like, involving a very simple, inexpensive combination of a rotary pump, electric motor and frame supporting such elements. In accordance with my construction the pump is entirely free of bearings and the arrangement is such that the motor shaft carries the rotor of the pump so that it operates in the case of the pump without touching any part thereof.

Another object of the invention is to provide a pump construction which is extremely simple, inexpensive and yet highly efficient. In the construction that I have provided the case of the pump is formed of two pieces of sheet metal and there is a permanent assembly of such pieces in which the rotor of the pump is permanently housed.

Another object of the present invention is to provide a circulating device of the character referred to including a rotary pump handling a substantial volume of water and having a natural tendency to create a circular motion of the body of water in which the pump is submerged, and including a baffle means which serves to effectively prevent or check such circular motion of the water.

In the ordinary rotary pump submerged in a body of water, as the pump operates there is a tendency for the entire body of water, and particularly the water in the vicinity of the inlet of the pump to start a circular or whirling motion, causing a whirlpool action which admits air into the pump. By my present invention I pro-

2

vide a baffle in connection with the pump that effectively checks or prevents the whirling action, eliminating all danger of air entering the pump to cut down its efficiency.

5 The various objects and features of my invention will be fully understood from the following detailed description of a typical preferred form and application of the invention, throughout which description reference is made to the accompanying drawings, in which:

Fig. 1 is a front or face elevation of the circulator provided by my invention, showing it ready for application to a cooler or the like, where the pump element of the apparatus will be submerged in a body of water. Fig. 2 is an enlarged plan view of the structure shown in Fig. 1, being a view taken substantially as indicated by line 2—2 on Fig. 1. Fig. 3 is a sectional view of the structure shown in Fig. 2, being a view taken as indicated by line 3—3 on Fig. 2. Fig. 4 is an enlarged detail view of a portion of the structure shown in Fig. 1, and Fig. 5 is a reduced sectional view taken on line 5—5 on Fig. 1.

The water circulator provided by my present invention can be used in various situations where it is desired to circulate water or other such liquids. In the drawings I have shown a form and arrangement of the present invention particularly suited for use in evaporative coolers for circulating the water employed to wet the evaporative pad or pads thereof, it being understood that I do not wish to thereby limit my invention to these or any other specific details.

The structure that I have provided involves, generally, a pump A which is a rotary pump, an electric motor B for driving the pump, a frame C mounting or supporting the pump and motor mounting means D by which the motor is mounted on the frame, and a baffle means E acting to prevent circular or whirling motion of the water in which the pump is submerged.

The pump A which I have provided and which involves several unique features of construction includes, generally, two end plates 10 and 11, a peripheral or side plate 12, and a rotor 13 operable in the case formed by the plates 10 and 11 and the side plate 12.

The side plates 10 and 11 may be plain, flat sheet metal plates suitably spaced apart to accommodate the rotor 13 and it is preferred that each of the plates has a central inlet opening 14. In the preferred construction one of the end or side plates, for instance, in the arrangement shown in the drawings, the upper plate 10, has 50 the side plate 12 formed integrally with it and

the side plate extends from the plate 10 to the plate 11 where it has an outwardly extending or outwardly turned flange 15 which is joined to the plate 11.

In accordance with my invention I permanently integrally join the flange 15 of the side plate 12 to the end plate 11 as by welding W. In the particular form of the invention illustrated the flange 15 and the plate 11 are welded together at a plurality of points or spots, as clearly shown in Fig. 2, so that these parts are integrally joined making the case a permanent or integral unit.

In accordance with my invention the rotor 13 is arranged within or between the two sections of the case when they are permanently joined together, as otherwise it would be impossible to get the rotor into the case.

The rotor 13 provided by my invention may be a simple, flat plate, round in plan configuration and mounted on the motor shaft 20 to be concentrically arranged in the case just described. In the form of the invention illustrated the flat plate of the rotor which operates in a plane normal to the axis of the shaft 20 has projecting vanes 21 which may be struck or otherwise formed on the plate in order to effectively act on the water within the case. In the preferred construction simple cuts are made in the plate of the rotor and the vanes are turned or formed by bending up parts adjacent the cuts. This makes a very simple, inexpensive construction.

The frame C provided by my invention may be varied in size, shape and character, depending upon the situation in which the unit is to be used. In the particular case illustrated the frame involves a simple base plate 30 which is a flat sheet metal plate having marginal flanges 31 which project from the forward or front side of the base plate and serve to stiffen the frame. The plate 30 may be provided with openings to accommodate screws 33, or the like, by which the plate can be made fast to a suitable support.

The pump A that I have provided is preferably located at the lower end portion of the frame C. In accordance with the preferred form of my invention the outer edge or marginal portion of the bottom plate 11 of the pump case is formed with a depending flange 35 which fits against the plate 30 and also engages and seats between the flanges 31. In practice I permanently secure, for instance spot weld, the flange 35 of the pump to the frame parts engaged by the flange, so that the pump is permanently and rigidly secured to the lower end portion of the frame. By forming the mounting flange 35 of the pump so that it depends, as shown in the drawings, I assure spacing of the bottom plate 11 from the bottom of a container in which the structure may be located to assure adequate water supply to the inlet opening 14 in the plate 11.

The motor B provided for driving the pump is preferably a simple, electric motor sealed in a case 40 and having a motor shaft 20 which projects from its upper end to carry a cooling fan 41 and depends from its lower end to enter the case of the pump A through the opening 14 in the upper plate 10 of the pump. In the preferred arrangement a collar 42 which may be an annular body of rubber, or the like, is applied to the motor shaft immediately below the case 40 to form a seal or check against water working up the shaft 20 to enter the motor.

The mounting means D for the motor is preferably a simple mounting construction involving straps 50 with flanges 51 at their inner ends per-

manently secured to the plate 30 of the frame, as by welding 52, and having flanges 53 at their outer ends joined by a suitable clamp screw 54. In practice a suitable pad or lining 55 is arranged between the straps 50 and the motor case, with the arrangement that I have provided and which is clearly illustrated in Fig. 1, the screw 54 can be tightened causing the motor to be firmly gripped and held stationary relative to the frame C so that the shaft 20 depends and projects into the case of the pump A.

It is to be observed that the opening 14 in the top plate 10 of the pump case is considerably larger in diameter than the shaft 20 of the motor so that the shaft fits into the case with substantial clearance.

In accordance with my invention I releasably connect the rotor 13 of the pump with the motor shaft. In the arrangement illustrated I provide screw threads 60 on the end portion of the motor shaft, that is on the part of the shaft which projects into the pump case, and I provide a pair of nuts 61 on the threaded part of the motor shaft, and I clamp the rotor of the pump between the nuts. With this arrangement it is a very simple matter to assemble the construction and make the rotor of the pump fast on the shaft in the proper position in the motor case. At any time that the motor should give trouble or should require replacement it is a simple matter to separate the pump rotor from the shaft by suitable manipulation of the nuts. It is to be observed that the nuts 61 on the shaft which hold the pump rotor are readily accessible through the openings 14 in the end plates of the pump case.

The baffle means E that I have provided preferably involves a simple baffle plate 70 arranged vertically above the case of the pump to extend in a substantially radial direction from a point adjacent the shaft 20. The baffle 70 may be a fixed baffle secured to any suitable fixed part of the structure. In the particular case illustrated I have shown the baffle provided with a mounting flange 71 which is secured to the base plate 30 of the frame C by welding 72. The baffle 70 is arranged close to the top of the pump case and may touch it or be somewhat spaced from it, as circumstances require. The inner end 75 of the baffle is spaced slightly from the shaft 20 so that the baffle in no way interferes with the operation of the motor shaft.

In operation the unit that I have described is mounted in a fixed position so that the case of the pump A and part or all of the baffle 70 are submerged in a body of water which is the water to be pumped. The motor is set in operation and as it operates the fan 40 circulates air in a manner to keep the motor cool and the collar 42 prevents water from creeping up the shaft into the motor.

As the motor operates the shaft 20 drives the rotor 13 at a high speed causing a circular motion of the water in the case. This causes water to be drawn into the case through the openings 14 and the water thus drawn into the case is delivered from the case to the outlet pipe 80 which is connected to the side wall 12 of the pump and which may be extended to any suitable point or may have any suitable conduit connected to it.

The pipe 80 is located at the peripheral part of the pump case and is preferably tangential thereto, as shown in Fig. 2, to effectively handle the flow created by the rotation of the rotor 13. As the pump rotates any tendency for the body of water in which the pump is rotated, and particularly the water immediately surrounding the

shaft 20, to rotate or form a whirlpool action is eliminated by the baffle 70 so that the pump is always maintained fully submerged and no air gets into it unless, indeed, the level of water drops so low that air enters the pump rather than water.

Having described only a typical preferred form and application of the invention, I do not wish to be limited or restricted to the specific details herein set forth, but wish to reserve to myself any variations or modifications that may appear to those skilled in the art, and fall within the scope of the following claims.

Having described my invention, I claim:

1. In combination a vertical frame member, a motor carried by the frame member and having a depending shaft, a liquid handling pump carried by the frame below the motor and including a case member with a central inlet opening into which the shaft extends with clearance and a rotor in the case member driven by the shaft, there being a peripheral outlet opening in said case, a vertically disposed baffle plate above the case member carried by one of the members and extending radially relative to the shaft to a point in the vicinity of the inlet opening to check circular motion of liquid in the vicinity of said opening.
2. In combination a vertical frame, a motor carried by the frame and having a depending shaft, a liquid handling pump carried by the frame below the motor and including a case with

a central inlet opening into which the shaft extends with clearance and a rotor in the case driven by the shaft, there being a peripheral outlet opening in said case, and a vertically disposed baffle plate carried by the frame above the case and extending radially relative to the shaft to a point in the vicinity of the inlet opening to check circular motion of liquid in the vicinity of said opening.

BRYANT ESSICK.
